UNITED STATES PATENT OFFICE.

WILLIAM L. LENGEL, OF READING, PENNSYLVANIA, ASSIGNOR TO THE NOLDE & HORST CO., OF READING, PENNSYLVANIA, A CORPORATION OF PENNSYLVANIA.

SEATING LOCK FOR KNITTING-MACHINE ATTACHMENTS OR THE LIKE.

Application filed April 4, 1922. Serial No. 549,584.

To all whom it may concern:

Be it known that I, WILLIAM L. LENGEL, a citizen of the United States, residing at Reading, in the county of Berks and State 5 of Pennsylvania, have invented certain new and useful Improvements in Seating Locks for Knitting-Machine Attachments or the like, of which the following is a specification.

10 My invention relates to a locking device adapted to secure a movable machine part in accurately seated relation to a relatively fixed part, and particularly applicable to knitting machine attachments as hereinafter 15 set forth; and it consists in improved clamping means adapted to be automatically operated during the seating or unseating movement, as fully described in connection with the accompanying drawings, and 20 the novel features of which are set forth in the subjoined claims.

Fig. 1 illustrates my invention applied in preferred manner, the drawing indicating a knitting machine having a striping thread 25 attachment, and showing my seating lock in connection with the vertically movable shaft of the latter, to which it is particularly adapted.

Fig. 2 shows an enlarged detail view of 30 my improved seating lock, the parts being indicated in seated and locked position and shown in section on the line 2—2 of Fig. 4.

Fig. 3 is a view similar to Fig. 2, but indicating the shaft raised from its seat.

35 Fig. 4 is a sectional plan view on the line 4—4 of Figs. 1 and 2.

Referring to the drawings, 1 represents the rotary needle cylinder of a known knitting machine, such as that set forth in 40 Hemphill Patent No. 933,443 of September seventh, 1909, 2 one of the circular series of needles commonly employed therein, and 3 a thread-carrier finger of a known cooperating striping thread attachment such as that set forth in Robinson Patent No. 1,214,826 of February sixth, 1917, and in my pending application Serial No. 543,142, filed March thirteenth, 1922. This finger 3 is commonly carried by a suspension plate 4 fixed to an 45 axially adjusted shaft 5 adapted to accurately position said finger in fixed relation to needles 2, or to raise the same to an elevated out-of-the-way position indicated in dotted lines in Fig. 1. The drawing shows 50 this shaft 5 splined in the sleeve 6 of a ro-

tary spindle table 7, carried in bracket 8 of a standard 9, with an extension 10 of the latter forming a top bearing for a sleeve ring 11, and a shaft 12 adapted to impart motion to table 7 from the needle cylinder driving mechanism through shaft gear 12^a and flange gear 7^a of said table as heretofore, to rotate shaft 5 in the sleeve 6 of the latter and carry suspended finger 3 around with the rotating needle cylinder 1. The axial shifting of shaft 5 may be accomplished in any well known manner, and in the drawings I have indicated a conveniently located handled lever 13 connected by a link 14 to a shifting lever 15, the latter, as shown, having a forked end 16 engaging studs 17 on a ring 18 loosely carried in an annular groove formed in a peripheral extension 19 of a shaft-moving sleeve 20, the opposite end 21 of said lever carrying a weight adapted to 75 nearly counter-balance the shaft and its attachments.

My seating lock, hereinafter specifically described, is particularly adaptable to an axially shiftable shaft such as shaft 5 above 80 described, to automatically lock the same in fully lowered and seated position, and to free the same preliminarily to reversely moving it.

The shaft-moving sleeve 20, as more 85 clearly seen in Figs. 2, 3 and 4, is preferably loosely mounted upon shaft 5, with a limited axial travel thereon between fixed collars 22 and 23, and is formed with a conical clamp-actuating portion 24. The collar 23, 90 as shown, is adapted to engage a fixed seat 25, and is carefully adjusted on shaft 5 to accurately position finger 3 when thus seated; and said collar is provided with a plurality of spring fingers 26, 26, arranged to 95 bear on the conical portion 24 of sleeve 20 to normally hold the latter in raised position against fixed collar 22, but yieldable under pressure to permit lowering movement of said sleeve toward collar 23. 100

Upon the upper end of the axially fixed sleeve 6, as shown, is secured an annular cap 27 having a collar extension 28, the upper surface of which forms the fixed seat 25 for the shaft collar 23. This extension 28 is 105 provided with opposite radial slots 29, 29 for clamping devices 30, 30, pivotally held in said slots by pivot pins 31, 31, and having upwardly projecting operating extensions 32, 32 adapted to be engaged and spread 110

2
by the clamp-actuating conical portion 24 of sleeve 20 when the latter is moved toward collar 23, thus clampingly engaging the ends 30, 30 with the shaft 5.

5 The operation of my device is as follows: Assuming the parts to be in the position shown in Fig. 3, and downward movement being imparted by lever 13 to shaft-moving sleeve 20, the latter will remain in contact 10 with collar 22, but will transmit axial downward movement to shaft 5 through collar 23, due to the frictional engagement of spring fingers 26 with the conical portion 24 of said sleeve, the latter remaining in this 15 raised position until it has moved said collar 23 into engagement with fixed seat 25. When the collar 23 is thus firmly seated on seat 25, further movement of sleeve 20 causes its independent travel on shaft 5, the springs 20 26, 26 yielding and riding up portion 24, but exerting a downward pressure on collar 23 to prevent any rebound tendency of the latter; and this travel of sleeve 20 carries its conical portion 24 into spreading engagement 25 with the operating extensions 32, 32 of clamping devices 30, 30, actuating the latter to engage and clamp the shaft 5 in firmly seated position, the parts now assuming the position indicated in Fig. 2. Upon reverse 30 movement of lever 13, the first action of sleeve 20 is an independent travel movement from collar 23 to collar 22, the shaft being held against movement by the clamps 30, 30; and this independent travel of sleeve 35 20 carries the latter out of engagement with the clamp extensions 32, 32, freeing the shaft from clamps 30, 30, and permitting engagement with collar 22 to raise said shaft, the spring fingers 26, 26 again engaging with 40 conical portion 24 to retain the sleeve in this position.

It will be understood from the foregoing description that my improved seating lock automatically effects the clamping of the 45 fully seated shaft, prevents any rebound movement, and firmly retains the shaft in seated position; and that the raising movement first acts to free the shaft from the seating lock preliminary to moving the shaft.

50 A seating screw 35 may be employed in seat 25 to minutely adjust the contact point, and it will be understood that my lock is equally applicable to a non-rotated shaft, and to other machines than knitting machines.

55 Modification and changes will obviously suggest themselves and I do not desire to limit myself to the specific mechanism shown and described.

What I claim is:

60 1. In a device of the character described, a fixed part, an axially movable part arranged to seat thereon, a clamping device for locking said movable part when seated, and a relatively movable clamp actuating 65 device carried by one of said parts and op-

erated by the seating and unseating movements.

2. In a device of the character described, a fixed part, an axially movable part arranged to seat thereon, a clamping device 70 for locking said movable part when seated, and a movement-imparting member comprising a relatively movable clamp-actuating device operated by the seating and unseating movements imparted by said member. 75

3. In a device of the character described, a fixed part, an axially movable part arranged to seat thereon, a clamping device for locking said movable part when seated, a movement-imparting member having a 80 limited idle movement, and a clamp-actuated device adapted to be operated during such idle movement preliminarily to the seating or unseating movements imparted by said member. 85

4. In a device of the character described, a fixed part, an axially movable part arranged to seat thereon, a clamping device for locking said movable part when seated, a movement-imparting member carrying a 90 clamp-actuating device and having a limited idle travel between fixed stops, and means adapted to hold said member against such travel until said parts are seated. 95

5. In a seating lock, the combination of a 95 fixed support, an axially movable shaft arranged to seat thereon and having fixed spaced collars, a shaft-clamping device, and a shaft-carried clamp-actuating sleeve movable between said collars when said shaft is seated. 100

6. In a seating lock, the combination of a 105 fixed support, an axially movable shaft arranged to seat thereon and having fixed spaced collars, a shaft-clamping device, and a clamp-actuating shaft-moving sleeve independently movable between said collars when said shaft is seated. 110

7. In a seating lock, the combination of a 110 fixed support, an axially movable shaft arranged to seat thereon and having fixed spaced collars, a shaft-clamping device, a clamp-actuating shaft-moving sleeve independently movable between said collars when said shaft is seated, and means to prevent such independent movement when said shaft is moved from its seat. 115

8. In a seating lock, the combination of a 120 fixed support, an axially movable shaft arranged to seat thereon and having fixed spaced collars, a shaft-clamping device, a clamp-actuating shaft-moving sleeve independently movable between said collars to operate said clamping device, and spring fingers on one of said collars adapted to normally prevent such independent sleeve movement. 125

In testimony whereof I affix my signature.

WILLIAM L. LENGEL.
